UNITED STATES PATENT OFFICE.

JOHN FETZER, OF PITTSBURGH, PENNSYLVANIA, ASSIGNEE OF FORTY ONE-HUNDREDTHS TO JOHN J. GERLACH, JR., OF PITTSBURGH, PENNSYLVANIA.

CENTRIFUGAL SEPARATOR FOR GASES.

1,004,760

Specification of Letters Patent.

Patented Oct. 3, 1911.

Application filed March 2, 1910. Serial No. 546,880.

To all whom it may concern:

Be it known that I, JOHN FETZER, a resident of Pittsburgh, in the county of Allegheny and State of Pennsylvania, have invented a new and useful Improvement in Centrifugal Separators for Gases, of which the following is a specification.

This invention relates to centrifugal separators and is designed more particularly for separating gases of different densities or specific gravities, such as the oxygen and nitrogen of the atmosphere.

The object of the invention is to provide a separator for the purpose specified which is of simple construction, effective in operation, and whereby the separation of the substances, such as the gases, can be regulated and a thorough separation secured.

The invention comprises the construction and arrangement of parts hereinafter described and claimed.

In the accompanying drawings, Figure 1 is a longitudinal sectional view of a separator embodying the invention, and Fig. 2 is in part an end elevation and in part a vertical transverse section thereof.

In the drawings, 1 indicates the frame of the machine, which may be of any suitable construction and which is provided with bearings 2 in which is mounted the shaft 3 of the rotor. The rotor comprises a suitable closed chamber 4 which preferably is of substantially frusto-conical shape as shown and which serves as the separating chamber.

This chamber is securely fastened to the shaft 3 and rotates therewith. In the chamber inside of the smaller head 5 is a transverse baffle plate 6 which extends out fairly close to the peripheral walls of the chamber, but not quite in contact therewith, leaving between its edges and the walls of the chamber the annular passage 7. This baffle plate is spaced from the head 5 by spacing sleeves 8 so as to provide the passage 9 between the same and said head. Similarly located inside of the chamber just forward of the larger head 10 is a baffle plate 11 which extends out into proximity to the walls of the chamber but leaving between its edges and said wall the annular space 12.

This plate is separated from the head 10 by spacing members 13 so as to leave between the same and said head the passage 14. The chamber is separated by one or more diametric or radial plates extending

longitudinally of the shaft, two of such radial plates 15 being shown, these plates being set in grooves in the baffle plates 6 and 11 and in the shaft 3 and outer walls 4 of said chamber, and dividing the chamber into two similar parts. These plates serve to carry the air or other material being separated around *en masse*.

The rotor 4 may be rotated by any suitable mechanism, the drawing showing for this purpose a pulley 17 secured to the forward end of the shaft 3. The forward end of the shaft is hollow to provide an inlet opening 18 for the gases or other substances to be separated. This is connected by means of a suitable swivel connection 19 to the supply pipe 20 for the gases or other substances to be separated. In order to produce a flow of gas through the apparatus, it is necessary to produce differences of pressure at the inlet and outlet ends. This can be accomplished either by attaching suction apparatus to the discharge outlets or forcing mechanism to the supply inlet. The drawings show diagrammatically a blower 21 connected to the inlet and serving as a means for producing the differences of pressure between the inlet and outlet and causing a flow of gas or other material through the apparatus.

The hollow portion 18 of shaft 3 extends inwardly to just inside of the head 5 of the casing and then communicates through cross ports or slots 23 with the passage 9 between said head and the baffle plate 6. The portion 24 of shaft 3 inside of the casing is either solid or plugged, so that no air can pass straight through the same. The other journal of the shaft is also hollow, for some distance inwardly beyond the larger head 10 of the casing, and in said hollow is inserted a pipe 25 of such size as to leave between itself and the hollow journal, an annular passage 26. The pipe 25 extends inwardly beyond baffle plate 11 and there communicates by cross ports or slots 27 directly with the chamber in casing 4. The annular space 26, however, extends inwardly only as far as baffle plate 11, and at its inner end communicates through cross ports or slots 28 with the space between baffle plate 11 and the head 10. The end of the outlet journal extends into and has a rotary bearing in a stationary fitting 30, which is provided with a discharge chamber 31 having a side outlet 32 which is controlled by a

valve 33. The central pipe 25 extends through chamber 31 and communicates with a side discharge opening 34 which is controlled by a valve 35. All of the swivel joints will be provided with suitable stuffing boxes or rings to prevent leakage of the gases.

In operation, the air, or other gases or liquids to be separated, is forced through the hollow shaft 3 and passes through cross ports 23 and flows radially outwardly through passage 9 and escapes through annular passage 7 at the outer edge of baffle plate 6. The air is carried around *en masse* by means of the division plates 15 and by centrifugal action is separated into its denser and lighter components. The denser component flows along the inner surface of the casing wall 4, and through the annular spaces 12 beyond the edge of baffle plate 11 and flows through the passage 14 through cross ports 28 and the annular space 26 in the hollow outlet journal and out through the discharge port 32. The lighter component of the gas flows inwardly in the separating chamber and through cross ports 27 into the central tube 25 and out through discharge port 34. By properly adjusting the discharge valves 33 and 35, the necessary separation of the components of the gas can be secured. For instance, discharge valve 35 will be set so as to preserve material pressure in passage 14 and at the annular space 12. Consequently, the lighter component of the gas cannot escape through said passage, but will be forced centrally of the separating chamber and out through the cross ports 27 as described. By varying the relative adjustment of valves 33 and 35, the relative amount of heavier component separated out from the gases or other substance can be regulated at will, as will be readily understood.

Preferably the heads of the chamber are somewhat convex as shown in order that the ports 23 and 28 may be quite long longitudinally of the axis, to pass sufficient air to compensate for the spaces at the peripheries of the baffle plates 6 and 11. The purpose of these baffle plates is to provide radial passages from the hollow shaft to the periphery of the chamber. These plates could, of course, be cast integral with the head, or in other words, the head could be of sufficient thickness to have formed therein the necessary radial passages.

While the apparatus described is intended primarily for separating gases into their denser and lighter components, it is obvious that it may be used for separating liquids as well as other substances. By means of it, it is possible to separate the oxygen from the nitrogen in the air, due to the different specific gravities of these two components.

What I claim is:

1. In a centrifugal separator, an imperforate casing inclosing a separating chamber, alining hollow journals on opposite sides of said casing and opening into the separating chamber, bearings in which said journals are rotatably mounted, one of said journals providing a supply inlet and the other journal being provided with separate discharge passages, and transverse plates in said casing extending into proximity to the chamber walls and providing unobstructed passages in the separating chamber arranged to direct the components of different specific gravities separately to said discharge outlets.

2. In a centrifugal separator, an imperforate casing of frusto conical form inclosing a separating chamber and provided with radial passages in proximity to each of its heads extending from its axis into proximity to its periphery, alining journals on opposite ends of said casing, the journal on the smaller end of said casing forming a supply inlet communicating with the radial passages at that head of the chamber and the other journal being provided with two outlet passages, one of which communicates with the chamber and the other with the radial passages at the larger head of the casing, and bearings in which said journals are rotatably mounted.

3. In a centrifugal separator, an imperforate casing of frusto conical shape inclosing a separating chamber, alining hollow journals on opposite ends of said casing and opening into the separating chamber, the journal on the smaller end of the casing forming a supply inlet and the other journal being provided with separate discharge passages, bearings in which said journals are rotatably mounted, and fixed transverse plates in said casing extending into proximity to the chamber walls and forming unobstructed passages arranged to direct the components of different specific gravities separately to said discharge outlets.

4. In a centrifugal separator, an imperforate casing inclosing a separating chamber, alining hollow journals on opposite ends of said casing and opening into the separating chamber, one of said journals forming a supply inlet and the other being provided with separate discharge passages, bearings in which said journals are rotatably mounted, and a baffle plate in said separating chamber adjacent to each end thereof and extending into proximity to the peripheral walls of said chamber and arranged respectively to direct the incoming gases to the periphery of the chamber and to direct the components of different specific gravities separately to the discharge outlets.

5. In a centrifugal separator, an imperforate casing inclosing a separating chamber, alining hollow journals on opposite ends of

said casing and opening into the separating chamber, one of said journals forming a supply inlet and the other being provided with separate discharge passages, bearings in 5 which said journals are rotatably mounted, and a transverse baffle plate in proximity to each of the heads of said chamber but separated therefrom and extending into proximity to the peripheral walls thereof, the supply journal communicating with the spaces between one of said heads and the baffle adjacent thereto, one of the discharge passages communicating with the spaces between the other head and the baffle adjacent 10 thereto, and the other discharge passage communicating with the chamber between the baffles.

6. In a centrifugal separator, an imperforate casing inclosing a separating chamber

and provided with radial passages in proximity to each of its heads extending from its axis into proximity to its periphery, alining hollow journals on opposite ends of said casing, one of said journals forming a supply inlet communicating with the radial passages at one of the heads of the chamber and the other journal being provided with two outlet passages, one of which communicates with the chamber and the other with the radial passages at the other head of the casing, and bearings in which said journals are 20 25 30 rotatably mounted.

In testimony whereof, I have hereunto set my hand.

JOHN FETZER.
